CENTERLESS GRINDING MACHINE

Loring Coes, Jr., Worcester, Mass., assignor to Norton Company, Worcester, Mass., a corporation of Massachusetts

Application December 31, 1956, Serial No. 631,828

4 Claims. (Cl. 51—129)

The invention relates to grinding machines and more particularly to a high speed centerless grinding machine. This invention relates to an improvement over my centerless grinding machine disclosed in my co-pending application Ser. No. 621,365, filed November 9, 1956.

One object of the invention is to provide a simple and thoroughly practical high speed centerless grinding machine. Another object is to provide a grinding wheel supporting and rotating mechanism for a grinding wheel having a plane operative face in which an outboard bearing support is provided for the wheel spindle to facilitate operation at high speeds. Another object is to provide a vertical adjustment for the grinding wheel so as to provide either a single grinding station or a pair of spaced grinding stations.

Another object is to provide a regulating wheel arrangement including a pair of spaced regulating wheels for supporting and rotating work pieces at the entrance and discharge ends of the grinding throat. Another object is to provide a pair of spaced regulating wheels on a rotatable spindle which are adjustable in an axial direction to facilitate positioning the regulating wheels so as to support and rotate work pieces entering and leaving the grinding throat in any adjusted position of the grinding wheel either when positioned for use as a single grinding station or as two spaced grinding stations. Another object of the invention is to provide suitable adjustments for the regulating wheel so that it may be adjustably swivelled, both in a horizontal and a vertical plane. Other objects will be in part obvious or in part pointed out hereinafter.

In the accompanying drawings in which is shown one of various embodiments of the mechanical features of this invention:

Fig. 1 is a front elevation of the centerless grinding machine, having parts broken away and shown in section; Fig. 2 is a plan view of the machine;

Fig. 3 is a right hand end elevation of the machine, taken approximately on the line 3—3 of Fig. 2, with the regulating wheel assembly removed so as to more fully illustrate the relationship of the grinding wheel and work rest;

Fig. 4 is a fragmentary sectional view, taken approximately on the line 4—4 of Fig. 2 through the regulating wheel assembly;

Fig. 5 is a fragmentary detail view, on an enlarged scale, of the swivel adjusting mechanism for the regulating wheel;

Fig. 6 is a fragmentary sectional view, on an enlarged scale, showing the mounting and axial adjusting mechanism for the regulating wheel; and

Fig. 7 is a fragmentary elevation showing the relationship of the grinding wheel, spaced regulating wheels, and work rest when the grinding wheel is raised vertically to its uppermost position.

A centerless grinding machine has been illustrated in the drawings comprising a base 10 which supports a transversely movable slide 11 on a dovetail slideway 12 formed

on the upper surface of the base 10. A feeding mechanism is provided for adjusting the slide 11 comprising a rotatable feed screw 13 which is rotatably journaled in a bracket 14 fastened to the left hand end of the machine base 10. The feed screw 13 meshes with or engages a threaded aperture 15 formed with the slide 11. A manually operable feed wheel 16 is provided for actuating the feed screw 13 for positioning the slide 11.

The transversely movable slide 11 serves as a support for a vertically adjustable wheel slide 20 which is arranged to slide vertically on a dovetail slideway 21 formed on a vertically extending projection 22 of the slide 11. The wheel slide 11 serves as a support for a rotatable wheel spindle 23 which is journaled in suitable bearings (not shown) for rotation at a relatively high speed. The wheel spindle 23 supports a grinding wheel unit 24, to be herein-after more fully described.

The driving mechanism is provided for rotating the wheel spindle 23 at a relatively high speed comprising an electric motor 25 which is adjustably mounted on the upper surface of the wheel slide 20. The motor 25 is provided with a motor shaft 26 which supports a multiple V-groove pulley 27. The pulley 27 is connected by multiple V-belts 28 with a multiple V-groove pulley 29 mounted on the left hand end of the wheel spindle 23 (Fig. 1).

A feeding mechanism is provided for adjusting the vertical slide 20 to facilitate positioning the grinding wheel unit 24. This mechanism comprises a feed screw 30 (Figs. 1 and 2), the upper end of which is rotatably supported by a plate 31 mounted on the upper surface of the vertical projection 22 of the slide 11. The plate 31 is provided with a bearing rotatably to support the upper end of the feed screw 30. The lower end of the feed screw 30 is supported by an anti-friction end thrust bearing 32 which is mounted on the transversely movable slide 11. The feed screw 30 meshes or engages a nut 33 which is fixedly mounted on the vertically movable slide 20.

The wheel slide 11 is also provided with a vertical cylindrical guidepost 34 the lower end of which is fastened to the slide 11. The slide 20 is provided with a projecting boss 35 having a cylindrical hole 36 therein which mates with the rod 34 and serves to support and guide the slide 20 as it is adjusted vertically by a rotary motion of the feed screw 30.

The grinding wheel unit 24 is arranged to support segment type wheel with only a relatively short portion of the segments projecting to provide a wheel capable of rotating at high speeds. As illustrated in Fig. 1, a wheel supporting plate 40 is mounted on a reduced portion 41 of the wheel spindle 23 and is held thereon by lock nuts 42. A plurality of bonded abrasive segments 43 are fastened to the plate 40 by screws 44. In order to support the segments against centrifugal force at high speeds, the segments are surrounded by a cup-shaped support 45 which is slidably keyed onto a threaded portion 46 of the wheel spindle 23. The internal surface of the cup-shaped support 45 is provided with a plurality of integral lugs 47. The lugs 47, as illustrated in Fig. 3 are preferably dovetail in shape and mates with grooves cut in the adjacent edge portions of adjacent segments. As illustrated in Fig. 1, the abrasive segments project from the right hand end of the support 45 only a relatively short distance so that the segments are supported to withstand centrifugal forces at high speed.

It is desirable to provide an adjustable support for the cup-shaped member 45 so that as the plane operative face of the segments wear away due to grinding, the cup-shaped support 45 may be adjusted toward the left (Fig. 1) to expose a desired portion of the segments,

In order to facilitate an axial adjustment of the member 45, a spanner type lock nut 48 is provided on the threaded portion 46 of the spindle 23. A cup-shaped nut 49 is also threaded onto the threaded portion 46 of the spindle 23 and is provided with a plurality of radially projecting pins 50 (only one of which is illustrated in Fig. 1) which ride in a groove formed in a hub portion 51 of the cup-shaped support 45. When it is desired to adjust the cup-shaped support 45 to expose a new portion of the segments after wheel wear, the lock nut 48 is backed-off after which the collar 49 is rotated to axially adjust the position of the cup-shaped support 45. After the member 45 has been adjusted, the lock nut 48 is again tightened to lock the member 45 in the new position.

In order to provide a more rigid support for the wheel spindle 23 adjacent to the plane operative face 65 of the grinding wheel when the spindle is rotated at high speeds, an outboard bearing 60 is provided to support a reduced end portion 61 of the wheel spindle 23. The bearing 60 is supported by a downwardly extending arm 62 which is fastened to a stud 63 carried by a bracket 64 which is formed either integrally or fixedly mounted onto the wheel slide 20. If desired to facilitate changing wheel segments, the arm 62 supporting the outboard bearing 60 may be unclamped from the stud 63 and removed therefrom.

The base 10 is provided with an upwardly extending projection 70 having an upper plane surface 71 which serves as a support for an angle iron bracket 72 (Figs. 1 and 3). The angle iron bracket 72 serves as a support for a work rest blade 73.

The angle iron bracket 72 is supported by a vertically arranged pivot stud 74 to facilitate an angular adjustment of the work rest blade 73 in a horizontal plane relative to the plane annular face 65 of the grinding wheel. A pair of spaced clamping screws 75 and 76 (Fig. 3) pass through elongated slots or enlarged holes 77 and 78, respectively, in the angle iron bracket 72 and are screw threaded into the upwardly extending projecting 70 of the base 10.

A plurality of clamping screws 79, 80, 81, and 82 pass through spaced vertically-arranged elongated slots 83, 84, 85, and 86, respectively, formed in the angle iron bracket 72 and are screw threaded into the work rest blade 73. It will be readily apparent from the foregoing disclosure that by loosening the clamping screws 75 and 76, the work rest blade 73 may be swivelled into the desired position relative to the operative face of the abrasive segments 43 after which the clamping screws may be tightened to lock the bracket 72 in adjusted position. The work rest blade 73 may be adjusted vertically relative to the grinding wheel unit 24 by means of loosening the clamping screws 79, 80, 81 and 82 and then adjusting the plate 73 vertically relative to the bracket 72 after which the clamping screws may again be tightened to lock the work rest blade 73 in adjusted position. The work rest blade 73 is provided with a bevelled work engaging and supporting surface 87 (Figs. 1 and 3).

The base 10 serves as a support for a transversely movable regulating wheel slide 95 which supports a regulating wheel unit 96. The slide 95 is arranged to slide along a dovetailed slideway 97 formed on the upper surface of the base 10.

A feeding mechanism is provided for the slide 95 comprising a rotatable feed screw 98 which is rotatably supported by a bracket 99. The bracket 99 is fixedly mounted on the right hand end of the base 10 (Figs. 1 and 2). The feed screw 98 meshes with or engages a nut 100 depending from the underside of the regulating wheel slide 95. A manually operable feed wheel 101 is mounted on the right hand end of the feed screw 98 to facilitate rotating the feed screw 98 in either di-

rection to cause a transverse adjustment of the slide 95 relative to the base 10.

The slide 95 is provided with an upwardly extending cylindrically-shaped column 105 which supports a frame 106. The frame 106 is provided with an internal cylindrical bore 107 which mates with the outer peripheral surface of the column 105. The frame 106 is provided with a slot 108 and a clamping screw 109 by means of which the frame 106 may be clamped in an adjusted position on the column 105 in adjusted position relative to the slide 95. This mounting just described serves to facilitate swivelling the regulating wheel unit in a horizontal plane about the vertical axis of the column 105.

The frame 106 serves as a support for a relatively large trunnion 110. The regulating wheel unit is arranged to fit over the frame 106 and is provided with a cylindrical bore 112 which mates with the outer peripheral surface of the trunnion 110. A screw adjusting mechanism is provided for swivelling the regulating wheel unit in a vertical plane about the horizontal axis of the trunnion 110. These swivelling adjusting mechanisms have been illustrated in Fig. 5 and comprises a pair of spaced blocks 116 and 117 which are fixedly screwed onto the regulating wheel unit 111. The blocks 116 and 117 support a pair of opposed axially aligned adjusting screws 118 and 119 respectively which are arranged to engage opposite sides of a stud 115 mounted on the frame 106. By manipulation of the screws 118 and 119, the regulating wheel head 111 may be swivelled about the horizontal axis of the trunnion 110 into the desired position.

The regulating wheel unit 111 serves as a support for a regulating wheel spindle 125 which is journaled in spaced anti-friction bearings 126 and 127 (Fig. 4). The regulating wheel spindle 125 supports a pair of spaced regulating wheels 128 and 129 which are preferably adjustably supported on the spindle 125 in a manner to be hereinafter described.

A suitable driving mechanism is provided for imparting a rotary motion to the regulating wheel spindle 125 at a relatively slow speed comprising an electric motor 130 which is mounted on the upper surface of the regulating wheel unit 96. The motor 130 is provided with a multiple V-groove pulley 131 which is connected by multiple V-belts 132 with a multiple V-groove pulley 133 which is supported on the driving shaft of a variable speed driving unit 134. The variable speed driving unit may be any one of the various variable speed driving units now on the market, such as, for example the Vickers speed change unit. The driven shaft of the unit 134 is provided with a multiple V-groove pulley 135 which is connected by multiple V-belts 136 with a multiple V-groove pulley 137 which is keyed onto the right hand end of the spindle 125. It will be readily apparent from the foregoing disclosure that when the motor 130 is started, a rotary motion will be imparted through the driving mechanism above described to rotate the regulating wheel spindle 125 and the regulating wheels 128 and 129 at a speed controlled by the speed change unit 134. The speed change unit 134 is provided with an adjusting knob 138 by means of which the speed of the regulating wheel spindle 125 may be varied as desired.

The spaced regulating wheels 128 and 129 are adjustably mounted on the spindle 125 to facilitate positioning the regulating wheels 128 and 129 so that in any vertical adjusted position of the grinding wheel the work piece 90 being ground will be supported by the regulating wheel at both the entering and discharge ends of the grinding throat.

As illustrated in Fig. 6 the regulating wheel 128 is supported on the wheel spindle 125 by a pair of clamping flanges 140 and 141 which are screw threaded onto a spindle 125. A slidably mounted key 142 which slides in a keyway 143 serves to lock the flange 141 in adjusted position relative to the spindle 125. When it is desired

to adjust the regulating wheel 128 in an axial direction, the flange 140 is backed-off after which the key 142 is moved toward the left (Fig. 6) and the flange 141 is then screwed along the spindle 125 to position the regulating wheel 128 into the desired position relative to the annular face 65 of the grinding wheel. The key 142 is then moved toward the right to lock the clamping flange 141 to the spindle 125 after which the flange 140 is rotated to clamp the regulating wheel 128 in adjusted position relative to the spindle 125. An identical supporting and adjusting mechanism is provided for the regulating wheel 129.

The work rest blade 73 is preferably positioned so that the work pieces to be ground are positioned slightly below the axis of the grinding wheel as shown in Fig. 1, the regulating wheels 128 and 129 are then adjusted along the spindle 125 so that the work piece 90 entering and leaving the grinding throat is supported by not only the work rest 73 but also by the regulating wheels 128 and 129. If it is desired to grind on the lower portion of the wheel as shown diagrammatically in Fig. 7, the wheel slide 20 is adjusted vertically so that a work piece 90 resting on the work rest 73 will pass across a chord at the lower portion of the plane annular face 65 of the grinding wheel. In this position of the grinding wheel, the regulating wheels 128 and 129 are adjusted in axial directions toward each other so that the work piece 90 will be supported and driven by the regulating wheels as the work piece enters and leaves the grinding throat formed by the said wheels. The outer side faces of the regulating wheels 128—129 are preferably positioned so that they are opposite to the outer periphery of the plane annular face 65 of the grinding wheel.

In setting up the grinding machine, the regulating wheel unit 95 may be swivelled in a horizontal plane about the axis of the post 105 so that there is a greater distance between the periphery of the regulating wheel 29 and the plane annular face 65 of the grinding wheel than there is between the regulating wheel 128 and the face 65, as shown in Fig. 2. With the parts in this position, the portion of the wheel at the entering end of the work rest blade 73 rough grinds the work piece and the other portion of the wheel face 65 finished grinds as the work piece passes through the grinding throat. The regulating wheel unit may also be swivelled about the horizontal axis of the trunnion 110 by manipulation of the screws 118 and 119 to swivel the axis of the regulating wheel spindle 125 in a vertical plane so as to produce the desired axial feeding component upon the work piece passing through the machine.

The operation of this improved centerless grinding machine will be readily apparent from the foregoing disclosure. Assuming that all of the adjustments to have been previously made, the motors 25 and 130 are started to impart a rotary motion to the grinding wheel unit 24 and the regulating wheels 128—129. Work pieces 90 to be ground may then be moved axially into the grinding throat where they are ground to the desired and predetermined extent. The slide 11 may be adjusted in a horizontal plane to adjust the grinding wheel unit. Similarly the slide 95 may be adjusted transversely relative to the base to position the regulating wheels 128—129 into the desired position relative to the work rest blade 73. After the plane annular face 65 of the grinding unit 24 is worn away due to grinding, the cup shape support 45 may be adjusted toward the left (Fig. 1) to expose a fresh portion of the abrasive segments 43.

It will thus be seen that there has been provided by this invention a centerless grinding machine in which the

various objects hereinabove set forth together with many thoroughly practical advantages are successfully achieved. As many possible embodiments may be made of the above invention and as many changes might be made in the embodiment above set forth, it is to be understood that all matter hereinbefore set forth are shown in the accompanying drawings is to be interpreted as illustrative and not in a limiting sense.

I claim:

- 10 1. A centerless grinding machine comprising a base, an adjustable slide on said base, a rotatable grinding wheel thereon having an annular plane grinding surface, means to rotate said grinding wheel at a high speed, a work rest adjustably mounted on said base extending substantially parallel to said annular plane surface so that the geometric projection of its top onto said plane surface defines two separated grinding areas on the annular surface, a regulating wheel unit including a slide adjustably mounted on said base, a regulating wheel spindle thereon, means to 15 rotate said spindle at a speed suitable for controlling work rotation, a pair of spaced regulating wheels on said spindle to support and rotate a work piece opposite separated grinding areas of the annular plane grinding surface and, means to swivel the regulating wheel unit in a horizontal plane about a vertical axis so that the space between the regulating wheel and the plane surface at the work entry end is slightly greater than the space between the other regulating wheel and the plane surface to facilitate rough grinding and then finish grinding on a work piece as it 20 passes axially through the machine.
2. A centerless grinding machine as claimed in claim 1, in combination with the parts and features therein specified of means to adjust said wheel slide vertically to vary the path of work pieces across the annular grinding face, 25 and means to adjust said regulating wheels axially relative to each other to facilitate positioning the operative peripheral faces of the regulating wheels relative to the spaced active portions of the annular face of the grinding wheel.
3. A centerless grinding machine, as claimed in claim 1, in combination with the parts and features therein specified of means to adjust said wheel slide transversely, means to adjust said wheel slide vertically to vary the path of work pieces across the annular grinding face, and means 30 to include adjustable flanges on said regulating wheel spindle to support said regulating wheels to facilitate adjusting said regulating wheels axially relative to each other so as to position the operative peripheral faces of the regulating wheels opposite to the separated grinding areas 35 of the annular face of the grinding wheel.
4. In a centerless grinding machine, as claimed in claim 1 in combination with the parts and features therein specified of an arm on said wheel slide, an outboard bearing on said arm rotatably to support the end of the grinding wheel spindle adjacent to the operative annular face of the grinding wheel to facilitate a high speed grinding operation.
